UNITED STATES PATENT OFFICE

SIGMOND G. WEILER, OF MILWAUKEE, WISCONSIN

DESIGN FOR A WALL STOVE

Application filed August 31, 1931. Serial No. 40,963. Term of patent 3½ years.

To all whom it may concern:

Be it known that I, SIGMOND G. WEILER, a citizen of the United States, residing at Milwaukee, in the county of Milwaukee and State of Wisconsin, have invented a new, original, and ornamental Design for a Wall Stove, of which the following is a specification, reference being had to the accompanying drawings, forming part thereof.

Figure 1 is a front elevation of the wall stove, with the closure doors in a closed position, the back being devoid of ornamentation;

I claim:

The ornamental design for a wall stove, as shown and described.

In testimony that I claim the foregoing I have hereunto set my hand at Milwaukee, in the county of Milwaukee and State of Wisconsin.

SIGMOND G. WEILER.
